UNITED STATES PATENT OFFICE

166,105

TRANSPORTABLE FIRE FIGHTING UNIT

Walter W. Schmitt and Walter H. Schmitt,
Grosse Pointe, Mich.

Application June 28, 1951, Serial No. 15,694

Term of patent 7 years

(Cl. D91—1)

To all whom it may concern:

Be it known that we, Walter W. Schmitt and Walter H. Schmitt, both citizens of the United States of America, both residents of the city of Grosse Pointe, in the county of Wayne, State of Michigan, have invented a new, original, and ornamental Design for a Transportable Fire Fighting Unit, of which the following is a specification, reference being had to the accompanying drawing, forming part thereof.

Fig. 1 is a perspective view of a transportable fire fighting unit embodying our new design;

Fig. 2 is a top plan view;

Fig. 3 is a side elevation;

Fig. 4 is a rear elevation; and

Fig. 5 is a front elevation.

The dominant features of our design reside in those portions shown by means of solid lines.

We claim:

The ornamental design for a transportable fire fighting unit, as shown and described.

WALTER W. SCHMITT.

WALTER H. SCHMITT.
